UNITED STATES PATENT OFFICE.

BENJAMIN A. MITCHELL, OF TOMPKINSVILLE, NEW YORK.

IMPELLER FOR VIBRATORS.

Application filed March 2, 1928. Serial No. 258,536.

This invention relates to vibrators of the general character of that shown in Letters Patent of the United States, No. 1,459,841, dated June 26, 1923, granted to the present applicant, in which a freely movable body, such as a ball, is caused by a rotating impeller to revolve about the axis of the impeller and within a race-way carried by the member which is to be vibrated or gyrated. The vibrators shown in said Letters Patent comprise a generally cylindrical housing which is supported at its middle portion so as to be capable of gyratory vibration about its center. Within the housing is a motor which drives an impeller shaft supported in suitable bearings in the housing and carrying at each end an impeller which drives a freely movable, eccentric body, such as a ball or roller, subject to centrifugal action, for coaction with a race-way secured in the housing. In that construction the freely movable body is placed in a recess in the impeller. The present improvement is concerned particularly with the means by which such freely movable body is carried by and revolved with the impeller in its rotation about its own axis. In accordance with the invention the ball or movable body is received within a guide sleeve which is itself swiveled upon an axis at right angles to the axis of the impeller shaft. The guide sleeve is supported so as to have limited freedom of movement in the direction of length of the impeller shaft and the freely movable body guided thereby and coacting with the race-way is therefore free to accommodate itself to the race-way. The wear on the impeller, which is a material factor at the high speed, say 3500 R. P. M., at which the vibrator is designed to operate, is thus reduced. The invention will be explained more fully hereinafter with reference to the accompanying drawing in which it is illustrated and in which:

Figure 1 is a view in longitudinal sectional elevation of a vibrator which embodies the invention.

Figure 2 is a view of the same in end elevation as seen from the right hand in Figure 1, with the end cap removed.

In the embodiment of the invention illustrated, a generally cylindrical housing 50 is supported at its middle portion so as to be capable of vibratory gyration about its center, being, in this case, the member to which the vibratory or gyratory movement is imparted.

It receives a motor 51 by which rapid rotation is imparted to the impeller shaft 52, supported in suitable bearings 53 in the housing 50. Also mounted in the housing 50, at each end thereof, is a race-way 54 for coaction, under the influence of centrifugal action, with a freely movable ball or intermediate member 55. Also mounted on the impeller shaft 52, at each end thereof, so as to rotate therewith, is an impeller, which, in the construction shown, comprises a tubular shell 56, which is keyed on the shaft 52, and a guide sleeve 57 which is swiveled, as at 58, on an axis at right angles with the axis of the shaft 52. The guide sleeve 57 receives with a free working fit the intermediate, freely movable ball 55, and has a somewhat loose fit within the tubular casing 56 so that it has limited freedom of movement in a longitudinal direction with respect to the impeller shaft. The ball 55, while thus driven by the impeller, is free to accommodate itself to the race-way.

It will be understood that the tubular casing 56 is diametrically arranged with respect to the impeller shaft and is extended equally on both sides and that it carries at each side a guide sleeve 57 so that the impeller is perfectly balanced, the vibratory gyration of the vibrated member 52 being effected by the freely movable ball 55 under the influence of centrifugal action.

I claim as my invention:

1. In a vibrator, the combination of a rotatable shaft, a member to be vibrated and having an internal race-way, a freely movable ball to coact with the race-way and subject to centrifugal action, and an impeller secured to the shaft and having a guide sleeve for the ball swiveled on an axis at right angles to the axis of the shaft.

2. In a vibrator, the combination of a rotatable shaft, a member to be vibrated and having an internal race-way, a freely movable ball to coact with the race-way and subject to centrifugal action, and an impeller secured to the shaft to rotate therewith and comprising a tubular casing secured to the shaft, and a guide sleeve swiveled in said casing on an axis at right angles to the axis of the shaft to receive the ball.

This specification signed this 28th day of February, A. D. 1928.

BENJAMIN A. MITCHELL.
